(57) **CLAIM**

The ornamental design for a perforated planter pot, as shown and described.

DESCRIPTION

FIG. 1 is a perspective view of a perforated planter pot, showing our new design;

FIG. 2 is a front view thereof with a rear view being a mirror image;

FIG. 3 is a left side view thereof with a right side view being a mirror image;

FIG. 4 is a top view thereof; and,

FIG. 5 is a bottom view thereof.

The broken lines depicted in FIGS. 1, 3, 4, and 5 represent perforation lines which form a part of the claimed design.
